DESIGN FOR A COMBINED WATCHCASE AND BAND

Robert A. Barré, New York, N. Y.

Application December 12, 1947, Serial No. 143,111

Term of patent 7 years

(Cl. D42—8)

To all whom it may concern:

Be it known that I, Robert A. Barré, a citizen of the United States of America, residing in the city of New York, county of Queens, and State of New York, have invented a new, original, and ornamental Design for a Combined Watch Case and Band, of which the following is a specification, reference being had to the accompanying drawing, forming part thereof, wherein the single figure of the drawing is a perspective view of a combined watch case and band, showing my new design; the band being shown in open position.

I claim:

The ornamental design for a combined watch case and band, substantially as shown.

ROBERT A. BARRÉ.
